E. L. CLARKE

WINDOW VENTILATOR

Filed Dec. 30, 1925

UNITED STATES PATENT OFFICE.

EDWARD L. CLARKE, OF SCRANTON, PENNSYLVANIA.

WINDOW VENTILATOR.

Application filed December 30, 1925. Serial No. 78,405.

- My invention relates to improvements in window ventilators to be used any place where a ventilator of this character is suitable.
- 5 The object of my invention is to provide a window ventilator adapted to be placed below the lower sash when raised to allow of the passage of air between the upper end of the lower sash and the lower end of the upper sash and by means of which when in operative position a supply of fresh air can enter the place and at the same time being so arranged as to eliminate draft of the supply of air.
- 10 Another object of my invention is to provide a ventilator of this character which can be readily applied and removed from the window and when placed in operative position beneath the lower sash completely closes the space made by raising the lower sash for the purpose above mentioned.
- 15 A further object of my invention is to provide a ventilator of this character which will not obstruct the light from entering the place and at the same time provide a simple, cheap and effective ventilator having certain details of structure and combination of parts hereinafter more fully set forth.
- In the accompanying drawings:—
- 20 Figure 1 is a perspective view of a window frame showing my improved ventilator applied below the lower sash.
- 25 Figure 2 is a transverse horizontal sectional view of Figure 1.
- 30 Figure 3 is a vertical transverse sectional view taken on the line 3—3 of Figure 1.
- 35 Referring now to the drawings 1 represents the frame of the window and 2 the lower sash, and 3 the upper sash, all of which are of the usual construction and need no further description.
- 40 My improved ventilator consists of two sections 4 and 5 hinged together at their inner ends as indicated at 6, and as shown these hinges are on the outside of the sections 4 and 5, so that any pressure from within the place will tend to lock the sections more tightly in the position shown in Figure 2 of the drawings when placed below the lower end of the sash, when said sash is in a raised position; and when placed beneath the lower sash in such raised position of windows of the usual construction by placing the outer ends of the sections 4 and 5 in the grooves 45 or guide-ways 7 and 8 in the frame which is clearly shown in Figure 2 of the drawings and against the outer face of the horizontal board which forms part of the lower part of the window frame, it becomes a self locking device and is held firmly in this position even without the aid of the lower sash resting upon it.
- 50 The tops of the sections 4 and 5 are rounded as indicated at 9 and the bottoms of said sections are rounded as indicated at 10 so as to meet the angle at which the bottom of the lower sash and the lower part of the window frame are made, and thus when the lower sash is resting upon this device when placed in the position above referred to, the 55 space left by raising the lower sash for the purpose above referred to, is completely closed, air entering as above stated between the lower end of the upper sash and the upper end of the lower sash.
- 55 The section 5 is provided with a handle 11 as shown in the drawings for convenience whereby the sections may be raised upwardly and drawn inwardly to break the hinge connection 6 for the purpose of removing the 60 ventilator from the window frame below the sash as shown in dotted lines in Figure 2 of the drawings. This handle also serves the same purpose for handling the ventilator in inserting it in the grooves or guide-ways 65 7 and 8 and placing it in the position shown in Figures 1 and 2 of the drawings. The frame or section 4 is provided with an eyebolt 12 to which is connected a chain 13 by means of snap hook 14. The opposite end of the chain 13 is provided with a snap hook 15 which snaps into a screw eye 16 secured to the lower part of the window frame 17 on the inside below the sill 18. This chain with snap hooks on both ends, is so arranged 70 to guard against the possibility of its being accidentally dropped on the outside of the window when being inserted or removed, the snap hooks being used so that it can easily be disconnected if for any purpose it is desired to take said ventilator away from the window. The two sections 4 and 5 can be made either solid or with glass panels 75 19 and 20 or other translucent material used in the panels which will admit light and thus when the device is applied practically the same amount of light will pass through the window into the place.
- 80 While I have shown and described this specific construction, it will be understood 85

that slight variations could be made therein without departing from my invention.

Having thus described my invention, what I claim is:—

5 A ventilator for application to a window frame having side grooves for a sash and a transversely slanting longitudinally shouldered sill, said ventilator comprising two sections hinged together on their outer faces
10 and adapted to be positioned beneath said sash with the ends of said sections seated in said grooves; a flexible connection attached to the inner face of one of said sections adjacent its hinged end and adapted
15 for attachment to a support, said connection constituting a means for breaking said ventilator at the hinge point whereby the section ends may be removed from said grooves, said connection further preventing
20 said ventilator from falling out of the window when inserting or removing the same; said ventilator sections being rounded top and bottom whereby to meet and tightly

25 contact against the adjacent sash rail bottom and the sill regardless of the transverse angle the same may have whereby to tightly seal the space between the said sash rail and window sill and permit the admission of air into the room between the top rail of said sash and the bottom rail of its companion sash; and the hinge of said sections being arranged to permit movement of the connected ends of the sections into the room upon elevation of the ventilator to clear the lower edge from said shoulder, said hinge preventing movement of the ends of said sections outwardly of the plane of said opposed frame grooves whereby the said grooves and the sill shoulder cooperate with said sections to hold the ventilator in place and against falling outwardly from said window when put in place.

30 35 40

In testimony whereof, I have signed this specification.

EDWARD L. CLARKE.
